(57) **CLAIM**

The ornamental design for a combined vacuum cleaner brush, broom, and telescoping wand, as shown and described.

DESCRIPTION

FIG. 1 is a bottom perspective view of a combined vacuum cleaner brush, broom and telescoping wand, with the broom unfolded and deployed, showing my new design;

FIG. 2 is a top, front perspective view thereof;

FIG. 3 is a top view thereof with the broom folded and retracted;

FIG. 4 is a bottom view thereof;

FIG. 5 is a right side view thereof;

FIG. 6 is a left side view thereof;

FIG. 7 is a rear view thereof;

FIG. 8 is a front view thereof;

FIG. 9 is a top, rear perspective view thereof;

FIG. 10 is a bottom, front perspective view thereof;

FIG. 11 is a top, rear perspective view thereof, with an outer

section of the telescoping wand partially extended;

FIG. 12 is a top, rear perspective view thereof, with an inner

section of the telescoping wand extended;

FIG. 13 is a top, rear perspective view thereof, with the inner

and outer sections of the telescoping wand extended;

FIG. 14 is a bottom, front perspective view thereof, with the

brush partially extended; and,

FIG. 15 is a bottom, front perspective view thereof, with the

brush fully extended.
